UNITED STATES PATENT OFFICE

103,993

DESIGN FOR A FOOD BOWL

Helen C. Keith, Kingston, Mass.

Application February 13, 1937, Serial No. 67,658

Term of patent 7 years

To whom it may concern:

Be it known that I, Helen C. Keith, a citizen of the United States, residing at Kingston, in the county of Plymouth and State of Massachusetts, have invented a new, original, and ornamental Design for Food Bowls, of which the following is the specification, reference being had to the accompanying drawing, forming part thereof.

In the drawing Fig. 1 is a top plan view of the bowl showing my new design and

Fig. 2 is a side elevation thereof.

The essential feature of my invention is the design of the handles for the bowl in the form of a partly opened ear of corn, as shown.

I claim:

The ornamental design for a food bowl, as shown and described.

HELEN C. KEITH.
